FASTENING

Edward H. Bastable, Jamaica Plain, Mass., assignor to United Shoe Machinery Corporation, Paterson, N. J., a corporation of New Jersey

Original application April 5, 1935, Serial No. 14,893. Divided and this application March 13, 1936, Serial No. 68,736

1. Claim. (Cl. 85—41)

This invention relates to fastenings, it being especially adapted for use in the assembly employed in performing the method described and claimed in the application for Letters Patent of the United States for improvements in the Art of attaching heels to shoes, filed in my name on April 5, 1935, and bearing the Serial No. 14,893, of which this application is a division.

In the attaching of shoe-heels, and particularly those of wood, it is a common practice to interpose an adhesive between the heel-seat-surface of a shoe and the cup of a heel which is to be applied thereto, and then to fix the heel temporarily in place by a screw-fastening until said adhesive has set. After this, the temporary fastening is removed, and permanent fastening means, as a screw or nails, inserted. On account of irregularities of the heel-seat-surface, and lack of correspondence between the contours of said surface and the cup of the heel which is to be seated thereon, it is difficult to obtain proper contact between the surfaces and therefore an adequate adhesive bonding. This difficulty is overcome by the improved method above mentioned and by the last-and-screw assembly employed in performing said method. The present invention has as an object the provision of a screw or like integral fastening so formed as to be capable, in such a connection, of applying to a shoe and its heel forces which will both urge the heel-seat-material into the cup of the heel and at the same time draw together the periphery of said cup and the heel-seat. This fastening has an elongated, cylindrical head, a screw-threaded shank of substantially the same length as the head and an intermediate hub. There are two annular shoulders between the head and shank, the shoulder farthest from the shank being the larger and gradually inclined toward the hub. This last-mentioned shoulder is for engagement with the last, while the other will contact with the inner surface of the heel-seat of a shoe upon the last. The threaded shank co-operates with the shoulders, when the fastening is in use, to draw a heel toward the parts engaged by said shoulders.

In the drawing,

Fig. 1 is a side elevation, with parts broken away and shown in section, of a shoe mounted on a last with which my improved fastening is to be employed;

Figs. 2 and 3 are fragmentary sections showing the rear portion of the last and shoe, the fastening means being associated with them and

occupying, respectively, its initial and final positions;

Fig. 4 is an enlarged side elevation of the fastening; and

Fig. 5 is a side elevation of a drill suitable for the formation of a hole for the reception of the fastening.

Referring to the drawing, the numeral 1 designates a last which may be of the usual type, except for such details as are hereinafter described pertaining to the present invention. As shown herein, it has the usual spindle-hole 2 and the nail-clinching plate 3 secured to the heel-seat portion. Upon the last appears a shoe S.

In accordance with my invention, the rear part of the last is provided with a substantially vertical bore or passage 10, which, for example, may be about 0.31" in diameter. The clinch-plate has a circular opening 11, substantially concentric with the bore 10 and being somewhat smaller in diameter, for example about 0.21", to provide an annular shoulder 12 which is in effect integral with the last.

My improved fastening 14 preferably consists of a unitary piece of case-hardened steel having a cylindrical head 15, which is furnished with means, such as a slot 16, for receiving a screw-driver or like tool. The diameter of the head is such as snugly to fit the bore 10 of the last, it being greater than the diameter of the opening 11 in the clinch-plate 3. The head-diameter may be about 0.30". The inner end of the head terminates in an annular inwardly beveled abutment or shoulder 18 engageable with the shoulder 12 of the last, as shown in Fig. 3. The bevel of the shoulder 18 facilitates the introduction of the fastening into the last-bore and furnishes more extended contact with the inclined surface of the shoulder 12. Next to the head is a cylindrical hub 19, this being slightly smaller in diameter than the opening in the clinch-plate, for example 0.195" to 0.200", the end 20 of the hub providing a second flat abutment or shoulder to engage the insole of a shoe on the last. The length of the hub may be varied in accordance with the heel to be attached, the thickness of the clinch-plate, etc. In all cases, it should be such as to project outwardly beyond the clinch-plate a distance sufficient to force the heel-seat material of the shoe S by contact of the shoulder 20 into close engagement with the cup of the heel to be attached. The shank or end 22 of the fastening 14 opposite the head is screw-threaded, the length being substantially that of the head 15.

15 and such as to enter the heel far enough to insure a firm grip, while its pitch may be substantially the same as an ordinary No. 10 wood-screw.

5 A drill 25 used to form a hole in the work to receive the threaded shank 22 should be of a size which will pass freely through the opening 11 in the plate 3, for example about 0.185" in diameter. The drill is shown as provided with 10 a shank 27 fitting the bore 19 of the last. Preferably, the end of the shank adjacent to the drill furnishes a shoulder 28 engageable with the last-shoulder 12, thus providing a stop which limits the depth of the hole to be drilled. The 15 drill may project outwardly beyond the shoulder 28 a distance sufficient to penetrate to a depth of approximately 0.5" into a heel 35 applied to the heel-seat of the shoe S.

20 My improved fastening may be utilized to perform the method already outlined in substantially the following manner: An insole 30, outsole 31, upper 32 and, if desired, a shank piece 33 of the shoe S are assembled about the last 1 with the margin of the upper turned over on to the under surface of the insole and secured thereto, as, for example, by lasting tacks. The 25 upper 32 may be understood to include an outer element, lining, doubler and counter, if such parts be employed. The shoe S may have the 30 outsole secured in any desired manner to the lasted insole and upper, and the rear part beveled at its edges to provide a suitable heel-seat for the cup of the heel 35, as is customary. Having prepared the shoe as above outlined, and 35 assuming that it is otherwise ready for the attachment of the heel, a coating of an adhesive 40 may be applied to the heel-seat-surface of the sole or to the cup-surface of the heel or to both, and having clamped the heel in contact with the 40 heel-seat, the drill 25 is introduced through the bore 19 and rotated to provide a hole 42 which extends through the insole 30, outsole 31 and shank-piece 33 and into the heel 35, as shown in Fig. 1. The engagement of the drill-shoulder 28 45 with the shoulder 12 of the clinch-plate, because of the substantially unvarying position of the stop which it furnishes upon all lasts, deter-

mines accurately the depth of the hole. After the drilling operation has been completed and the drill withdrawn, the fastening 14 is inserted, and by means of a screw-driver or other tool is rotated to cause the shank 22 to cut its way 5 into the wall of the heel-opening 42, forming a thread therein. During the movement of the fastening, the heel is drawn toward the last by the engagement of the shoulder 18 with the shoulder 12 of the last. By reason of the engagement of the shoulder 20 of the fastening with the insole of the shoe, the heel-seat is simultaneously forced away from the last into close contact with the cupped surface of the heel, as will appear by a comparison of Figs. 10 15 and 3. As the force exerted by the shoulder 18 of the fastening is against the clinch-plate, rigidly secured to the last, a very powerful 20 clamping action is exerted and the heel is firmly drawn against the heel-seat with sufficient pressure to produce a tight crease and to enable the adhesive, while setting, to develop its maximum holding effect. After having maintained the engagement between the heel and heel-seat long enough for the adhesive to set thoroughly, the 25 fastening 14 is removed.

Having thus described my invention, what I claim as new and desire to secure by Letters Patent of the United States is:

An integral fastening for use in temporarily securing a heel to the heel-seat of a shoe mounted upon a last provided with a clinch-plate, said fastening comprising an elongated, cylindrical head of substantially uniform diameter throughout its length, a cylindrical hub of less diameter and less length than the head and projecting therefrom, the head terminating at its inner end in a shoulder inclined gradually toward the hub and arranged to engage the clinch-plate of the last and said hub having at its inner end a flat 35 shoulder of less diameter than the inclined shoulder and arranged to engage the heel-seat portion of the shoe upon the last, and a threaded shank of less diameter than the hub and projecting therefrom, the shank and head being of 40 substantially the same length.

EDWARD H. BASTABLE.
